UNITED STATES PATENT OFFICE.

GEORGE L. PIERCE, OF MANCHESTER, NEW HAMPSHIRE, ASSIGNOR TO PRESTO SPINNING RING HOLDER COMPANY, OF BOSTON, MASSACHUSETTS, A CORPORATION OF MAINE.

SPINNING-RING HOLDER.

1,098,525.

Specification of Letters Patent.

Patented June 2, 1914.

Application filed March 8, 1909. Serial No. 481,873.

To all whom it may concern:

Be it known that I, GEORGE L. PIERCE, a citizen of the United States, residing at Manchester, county of Hillsboro, and State 5 of New Hampshire, have invented an Improvement in Spinning-Ring Holders, of which the following description, in connection with the accompanying drawing, is a specification, like letters on the drawing 10 representing like parts.

This invention relates to a spinning ring holder of that type which is removably secured to the ring rail without the use of screws.

15 My present invention consists in providing the ring rail with a plurality of inwardly-directed fingers which are adapted to overlie the upper surface of the ring holder, and in providing the ring holder 20 with notches in its periphery which are adapted to receive the fingers whereby after the ring holder is properly positioned on the rail plate a turning movement of the ring holder will carry portions thereof adjacent 25 the notches underneath the fingers.

I will first describe one embodiment of my invention and then point out the novel features thereof in the appended claims.

Figure 1 is a plan view of a spinning ring 30 embodying my invention showing the ring holder secured to the rail plates; Fig. 2 is a plan view of the rail plate; Fig. 3 is a plan view of the spinning ring and its holder removed from the rail plate; Fig. 35 4 is an enlarged sectional view on the line $x-x$, Fig. 1; Fig. 5 is a section on the line $y-y$, Fig. 1.

3 designates the ring rail, 4 the rail plate, 5 the ring holder, 6 the spinning ring, and 40 7 the traveler. The spinning ring and traveler may have any suitable or usual construction, and said spinning ring is shown as secured to the ring holder 5 in usual manner by means of the lips 8. The rail plate may be secured to the ring rail 3 in any suitable way, and I have herein shown 45 said rail plate as provided with the tubular neck 9 which passes down through the ring rail and is secured thereto by a screw or other connection 10. The parts as thus far described may have any suitable or usual construction and form no part of my invention.

50 My improved rail plate is provided with the inwardly-directed fingers 11 which are

shaped to embrace the edge of the ring holder. These fingers may have different shapes and can conveniently be made by making the flange of the ring rail with radially-extending arms which are bent over 60 or doubled on themselves to form the fingers. Said fingers preferably have a portion extending parallel with the flange 4 and situated therefrom a sufficient distance to provide a space to receive the edge of 65 the ring-holder. The ring holder 5 is made with a plurality of notches 13, each of a size to receive one of the fingers 11, said ring holder being made at one side of each notch with an abrupt stop shoulder 14, and 70 being formed at the other side of the notch to present a portion 15 having its periphery at a radial distance from the center of the ring holder equal to or slightly less than the radial distance of the vertical portion 75 16 of the fingers. Each portion 15 of the ring holder terminates in a stop shoulder 17. In applying the ring holder to the rail plate, said holder is positioned above the rail plate so that the notches 13 come 80 directly above the fingers 11, and when in this position the ring holder may be dropped onto the rail plate, the fingers 11 passing through the notches 13, as will be obvious. If the ring holder is now turned 85 the portions 15 thereof will pass under the fingers 11, as shown in Figs. 1, 4 and 5, and the ring holder will thus be securely held to the rail plate. The stop shoulders 17 limit the turning movement necessary to 90 connect the ring holder to the rail plate.

The fingers 11 are preferably resilient and are so arranged that they will have sufficient frictional engagement with the upper surface of the ring holder to firmly retain said 95 ring holder in place.

If it is desired to remove the ring holder from the rail plate said ring holder is turned in the opposite direction until the shoulders 14 engage the fingers when said ring holder 100 can be lifted vertically from the rail plate.

I have herein shown in dotted lines a suitable tool or implement for turning the ring holder to lock it to or unlock it from the rail plate. This tool is shown as provided with a handle 20 formed at its end with two arms 21 that terminate in downwardly-directed portions 22 the extremities of which are adapted to enter apertures 23 formed in the ring holder. The two arms 21 are so 110

shaped that they do not interfere with the spindle which will be situated within the spinning ring.

Having fully described my invention, 5 what I claim as new and desire to secure by Letters Patent is:—

1. In a spinning ring, the combination with a ring rail, of a rail plate rigidly secured thereto and having a flat upper face 10 and integral inwardly-directed resilient holding fingers at its edge which are situated above said face, and a ring holder adapted to rest on said rail plate with its edge confined beneath and in frictional engagement 15 with the fingers, said ring holder having a plurality of similar notches in its outer edge spaced to correspond to the position of the fingers and of a depth to permit the ring holder to be removed in an axial direction when it is turned concentrically to bring the notches in alinement with the fingers.

2. In a spinning ring, the combination with a rail plate having holding fingers integral therewith at its periphery, each provided with a vertical portion and an inwardly-directed portion at the upper end of the vertical portion, of a ring holder having similar notches in its outer edge through 25 which the fingers may pass when the holder is applied to the rail plate in an axial direction, said holder having portions adjacent

said notches with the perimeter at a radial distance from the center less than that of the vertical portions of the fingers and also 35 less than that of the outer edge of said holder whereby turning movement of the holder about its axis carries said portions underneath the fingers.

3. In a spinning ring, the combination 40 with a rail plate having holding fingers, each provided with a vertical portion and an inwardly-directed portion, of a ring holder having similar notches in its outer edge to receive the fingers when the holder is 45 applied to the rail plate in an axial direction and having a portion adjacent each notch, the perimeter of which portion is at a radial distance from the center of the ring less than that of the vertical portions of the 50 fingers whereby turning movement of the holder about its axis carries said portions underneath the fingers, said portions terminating in stop shoulders to engage the 55 fingers and limit the turning movement of the ring holder.

In testimony whereof, I have signed my name to this specification, in the presence of two subscribing witnesses.

GEORGE L. PIERCE.
